UNITED STATES PATENT OFFICE.

ARTHUR HAENICKE, OF BERLIN-TEMPELHOF, GERMANY.

MACHINE FOR SEWING ON BUTTONS.

Application filed September 23, 1925. Serial No. 58,170.

Buttons of all kinds are sold sewn on to cards, the number of buttons in a row and the distance between the rows differing according to the size of the buttons. This difference in the number of buttons and in the distance between the rows was one of the difficulties which has hitherto prevented buttons being sewn on to cards entirely by machinery.

Consequently in the methods at present in use the buttons had to be placed one by one by hand in correct position on the card and had to be held there, until the sewing operation by the sewing machine had been started.

The present invention provides an arrangement which enables the buttons to be sewn on entirely by machinery, without the number of buttons to the row or the distance between the rows causing any difficulty and without the necessity of each button being held in position by hand. The device is not only suitable for sewing buttons on to cards, but also for sewing single buttons or rows of buttons on to woven fabrics and the like.

Provision is made for conveying the buttons automatically from a magazine to the place where they are to be sewn on, the arrangement being such that, should a button be in a wrong position or should no button be forthcoming, the apparatus is automatically thrown out of action, so that the person attending to it must intervene.

The invention is illustrated by way of example in the accompanying drawings, in which—

Figure 1 is a vertical longitudinal section through the device.

Figure 2 a vertical transverse section on line II—II of Figure 1,

Figure 3 a plan view of a detail to an enlarged scale and

Figure 4 a front elevation of this detail.

According to the invention in a machine frame 1, in which the various parts of the sewing mechanism 1^a are journaled, a slide 2 is mounted so as to be capable of sliding therein. For this purpose a guide 3 is provided, on which it slides easily for instance with the aid of balls 4. The slide is traversed by means of a lever 5 pivoted at a point 6 on the base of the machine and connected to the slide by the link 7. On the lever 5 is a roller 8, which coacts with a cam disc 9 on a shaft 10. As the slide must be moved intermittently, a star wheel 11 is provided in the actuating mechanism for the

cam disc 9, in which star wheel a pin 12 on a disc 13 engages. The star wheel is in operative connection through toothed gearing or the like 14, 15 with the shaft 10 of the cam disc 9 and the disc 13 is driven in any suitable manner from a main driving wheel 16, for instance through gear wheels 17, 18 and bevel wheels 19, 20. This arrangement provides for the sliding motion required for the sewing on of the separate buttons one behind the other in a row.

For fixing the card on the slide, bars 21 with guiding grooves are provided, into which the card 22 is inserted and which allow of the card being displaced in a direction at right angles to the direction of motion of the slide.

The following arrangement is provided for advancing the card or other support after a row of buttons have been sewn on:

In the slide on a shaft 23 a long pinion 24 is rotatably mounted. On this shaft are fixed wheels 25, 26 with sharp teeth, which are adapted to get a grip of the card or other support with these teeth and, on being rotated, to feed the same forward. The pinion 24 may be connected to the shaft 23 through either of two couplings 27 and 28, which act in opposite directions. The pinion can be displaced laterally by a resilient arm 29, whereby either the coupling 27 or the coupling 28 can be caused to engage.

Normally two springs 30 and 31 keep the arm 29 in such a position that neither of the two couplings 27 and 28 is in engagement. The pinion 24 is turned by means of a toothed sector 32, which meshes with it and which is operated by a cranked lever 33, which is connected to it, from a cam 34, the rotation of the gripping wheels 25 and 26 only taking place in one direction, when the couplings are in engagement.

As long as the buttons of one row are being sewn on, the arm 29 and consequently the pinion 24 is in its middle position, so that, while it is turned forwards and backwards through the motion of the toothed sector 32, it does not transmit this motion to the gripping wheels 25 and 26. As soon as the last button has been sewn on and the slide has therefore reached the end of its travel, the arm 29 strikes against a yielding stop 35 on a lever 36. This causes the arm 29 to swing aside and one of the couplings, in this case the coupling 27, to engage, so that the motion of the pinion derived from the sector

32 is transmitted to the gripping wheels 25, 26 and the card or other support is displaced by the distance between the rows of buttons. The first button of the new row is sewn on and, as the slide moves back under the action of the cam disc 9, the arm 29 ceases to engage with the stop member 35, the pinion 24 is uncoupled and there will be no further displacement of the cards, until the slide on 5 reaches the end of its traversing motion strikes against another stop member 37. This is the case, when the last button of the next row has been sewn on. In this case the lever 29 is thrown over in the other direction 10 and the coupling 28 caused to engage, whereupon the card is again fed forward by the distance between the rows of buttons and the cycle of operations is repeated. The stop members 35 and 37 are mounted yielding 15 in the arms 36 and 40, springs 38 and 39 being provided for this purpose, so that, even when the arm 29 rests against one of them during the to and fro motion of the toothed sector the couplings 27 and 28 can 20 engage. By means of a bar 41 connecting the two arms 36 and 40 the distance between the stop members and thereby the commencement of the forward feed of the card can 25 be accurately adjusted. The amount of forward feed of the card is adjusted for by an 30 adjusting screw 42 which according to its position allows the toothed sector 32 to be moved through a greater or smaller angle and to transmit a greater or smaller angle 35 of rotation to the pinion.

For holding the button in position, when being sewn on, a button holder 43 is provided, which is raised and lowered by a cam disc 44. On a part of the machine adjacent 40 to the slide 2 a stop member 45 in the form of a bar or an angle piece is provided, against which the buttons are placed by the person attending to the machine. A feed arm 46 is provided, which has two downwardly directed teeth 47, the object of which 45 is to enter the holes in the button, grip the latter in this manner and bring it forward to the needle in the correct position for sewing. The feed arm 46 is pivoted to a lever, 50 a bar 49 being provided on the said lever, which imparts a raising and lowering motion to the feed arm. In the button holder 43 is a recess 50, through which the end of the feed arm 46 can pass for bringing the 55 button into the correct position immediately below the button holder.

The device just described takes hold of the button resting against the member 45 by the teeth 47 entering the holes in the button 60 and, on the lever 48 performing a swinging motion, moves the button under the button holder, whereupon the latter descends and grips the button. The feed arm is thereupon raised and moved aside for fetching the next 65 button.

The described arrangement of the feed mechanism makes it possible for the button to be brought in its correct position to the sewing point, whereby a considerable saving in time is effected, and, owing to the member 70 45 being positioned externally of the slide the attendant will find it easy to hold the button in readiness at this place.

What I claim is:—

1. A machine for sewing buttons on to 75 cards, consisting in the combination of a machine frame, a displaceable slide, a guide on the machine frame for the displaceable slide, a plate on the slide adapted to serve as a bearing surface for a card, covering 80 ledges with guiding grooves for the card, a swinging lever with one end supported in the machine frame and with the other end connected by a rod with the slide, a cam disc driven from a main driving shaft and 85 acting on said swinging lever for the intermittent movement of the slide and of the card placed thereon in one direction, a holding device for a button over the slide, a conveying device for bringing a button under 90 said holding device, and a sewing device under the slide for sewing the button on the card.

2. A machine for sewing buttons on to 95 cards, consisting in the combination of a machine frame, a displaceable slide, a guide on the machine frame for the displaceable slide, a plate on the slide adapted to serve as a bearing surface for a card, covering 100 ledges with guiding grooves for the card, a swinging lever with one end supported in the machine frame and with the other end connected by a rod with the slide, a cam disc driven from a main driving shaft 105 by an intermittently advanced star wheel and acting for the intermittent movement of the slide and of the card placed thereon in one direction, a sleeve-shaped holding device for gripping the edge of the button over the slide, a cam for raising and lowering 110 the holding device, a stop margin outside the movable slide as a storage place for the buttons that are to be sewn on, an oscillatably supported feeding arm for taking a button away from the stop margin 115 and bringing a button under said holding device, an eccentric device for moving said feeding arm, and a sewing device under the slide for sewing the button on to the card.

3. A machine for sewing buttons on to 120 cards, consisting in the combination of a machine frame, a displaceable slide, a guide on the machine frame for the displaceable slide, side walls on said slide, a bearing surface secured to said side walls for a card, covering 125 ledges with guiding grooves for the card, a swinging lever with one end supported in the machine frame and with the other end connected by a rod with one side wall of the slide, a cam disc driven from 130

a main driving shaft by an intermittently advanced star wheel for the intermittent movement of the slide with the card in one direction, a shaft journaled in the side walls of the slide, wheels with sharp edged teeth rigidly connected with said shaft for moving the card in a direction perpendicular to the direction of movement of the slide, a long pinion freely rotatable and 10 slidable on the said shaft, a toothed sector engaging with said pinion in every position of the slide, driven by a cam disc and having a swinging movement, clutch members on the wheels with sharp edged teeth for 15 the moving of the card, clutch members on the ends of the pinion, a spring device normally holding the pinion in a central position out of engagement with the clutch members on the wheels with the sharp edged teeth, and means for coupling the pinion 20 with one of said wheels with sharp edged teeth in each of the end positions of the slide, a sleeve shaped holding device over the slide for securing the edge of the button, an eccentric arrangement for raising and 25 lowering the holding device, a stop margin outside the displaceable slide as a storage place for the buttons, an oscillatably supported feeding arm for taking a button away from the stop margin and bringing a button under said holding device, a cam 30 for moving said feeding arm, and a sewing device under the slide for sewing the button on to the card.

In testimony whereof I have signed my 35 name to this specification.

ARTHUR HAENICKE.
